NAIL POLISH APPLICATOR

Carl C. Hoffman, Jr., St. Louis, Mo., assignor
to Carl C. Hoffman, Inc., St. Louis, Mo., a corporation of Missouri

Application June 30, 1936, Serial No. 88,253

6 Claims. (Cl. 132—73)

This invention relates to reservoir-carrying applicators, and more particularly to an applicator adapted to carry a relatively viscous liquid and deposit the same upon a brush or the like in a position ready for application.

The principal object of the invention is to provide a hand applicator, particularly adapted for a sticky, somewhat thick, rapidly drying liquid, carried in a housing forming a portion of the applicator, and ejected from the housing, when required, upon a suitable applying surface.

Another object is to provide such an applicator, whereby the flow of liquid may be regulated.

Still another object is to provide such an applicator, whereby the volume of fluid ejected may be easily controlled and the fluid applied to a relatively small surface, the confines of which surface may be variously curved.

Another object is to provide an applicator, as set out, whereby manipulation of the applicator will tend to prevent thickening of the rapidly drying viscous liquid contained in the reservoir.

Yet another object is to provide an applicator, as described, which will be low in cost of manufacture.

Other objects and advantages of the invention will be apparent during the course of the following detailed description, taken in connection with the accompanying drawing, forming a part 30 of this specification and in which drawing:—

Figure 1 is a longitudinal section of the novel applicator.

Figure 2 is an enlarged fragmentary longitudinal section of the liquid-applying end of the applicator.

Figure 3 is an enlarged elevation of the fragment shown in Figure 2.

Figure 4 is a view showing the novel applicator in use.

Figure 5 is a section of a cap suitable for the applicator.

In the drawing, wherein for the purpose of illustration is shown only a preferred embodiment of the invention and wherein similar reference characters designate corresponding parts throughout the several views, the letter A may designate the novel applicator, B a cap therefor and C liquid carried by the applicator A.

The applicator A preferably includes a tubular portion 10, of rigid material such as metal, hard rubber, glass or the like. This tubular portion 10 has a closed end 11, is open at its other end 12 and may be provided, adjacent this end 12, with a shoulder 13 by slightly restricting the circumference of the tubular portion 10 at the end 12.

Closing this end 12 is a suitable hollow cap or closure portion 14, of flexible material, such as soft rubber, this cap having a side wall 15 of a length so that, when it is disposed with a portion snugly embracing the end 12 of the tubular portion 10 and with its extremity 16 abutting the shoulder 13, the cap portion 14 will extend an appreciable distance beyond the open end 12 of the tubular portion 10. By an appreciable distance is meant at least a distance as great as 10 the width of the ball portion of a thumb and this distance may be greater altho, for the purpose of proper manipulation of the applicator, the distance is preferably not over one and one-half 15 inches.

The cap portion 14 is provided with an end wall 17, having a restricted opening or outlet 18, preferably spaced from the longitudinal axis of the cap portion 14. This opening may be a perforation or a slit. Extending inwardly from 20 substantially the longitudinal axis of the cap portion 14 is a recess 19, the wall 20 of which preferably comprises the same material as that of the rest of the cap portion 14. This wall 20 provides a thimble which extends inwardly of the cap portion, as is well shown in Figure 2, and with said wall 20 spaced substantially an equal distance from the side wall 15 of the cap portion 14. The mouth of the recess opens, as is apparent, exteriorly of the cap portion 14.

For a purpose later described in detail, a guide and drip-preventing means is provided which preferably comprises a projection or baffle 21 secured in any approved way to the exterior surface of the end wall 17 or, it may be molded as a portion thereof. This baffle 21 extends partly about the outer mouth of the opening 18 in a position so that the opening is between it and the mouth of the recess 19. Furthermore, the baffle extends outwardly from the end wall 17, but slightly 40 toward the longitudinal axis of the cap portion 14.

As a means to apply the liquid employed, it is preferred to make use of a suitable number of bunched together bristles or hairs 22 of suitable 45 material, so that a flexible portion may be provided. The bristles 22 preferably are held in their bunched together position and gripped by a rigid portion 23, which may be a tube of suitable material, such as a short quill, disposed 50 snugly within the recess 19, with the flexible portion, i. e., the bristles 22, projecting outwardly, as shown in Figures 1 and 2.

With the cap portion 14 in place, as shown in Figure 1, there is provided a slim or elongated 55

hollow body portion, somewhat like a fountain pen in size and shape, defining a reservoir 21, the greater part of this body portion being, preferably, of rigid material, but with one extremity 5 flexible as described.

The cap 18 may be of any suitable material, such as metal, rubber or the like, and includes a substantially cup-shaped portion 25, adapted to extend about the flexible extremity of the hollow 10 body portion just described, and a bristle-receiving portion 26, adapted to receive and extend about the bristles 22.

As has been stated, the applicator is particularly adapted to carry and discharge a relatively 15 viscous liquid, such as conventional liquid nail polish. This may be introduced by removing the cap portion 14 and filling the reservoir 21, then replacing the cap portion 14. Such liquid, shown as C, while it will flow, requires care in its application since it is generally sticky but dries quite rapidly and must be applied so that the coating is not too thick. Since the area coated (the 20 nails) is irregular in outline and restricted, the problems mentioned in applying the polish are 25 not the ordinary problems encountered in applying paints to surfaces in general, water to surfaces to be cleaned, nor liquid free of viscous characteristics to surfaces in general. In order to employ such viscous liquids as nail polish, it is 30 preferred that the greater portion of the wall of the reservoir should be rigid, not only because the liquid is heavy but also so that the wall will not become distorted while the flexible cap portion 14 is being manipulated. This cap portion 35 14 must be flexible and thus admits the applicator to be grasped substantially as shown in Figure 4, by the thumb and index finger of the hand but, preferably nearer the end wall 17, and by squeezing the flexible cap portion 14, the outlet 40 let 18, positioned as it is, close to the end of the cap portion, will be enlarged or fully opened allowing an initial flow of some volume of liquid, or, after the applicator has been closed by the 45 drying of the liquid thereon, the outlet may be reopened by such manipulation. Then, the thumb and index finger may travel up the cap portion 14 and hold the applicator substantially as shown in Figure 4, with a sufficient pressure upon the flexible cap portion to provide for a 50 suitable flow of the liquid, which flow will not be quite as great, since the outlet will not be opened as wide as when the cap portion is squeezed closely adjacent the outlet. However, the flow can be regulated somewhat according to 55 the pressure applied to the cap portion when the thumb and finger squeeze it as shown in Figure 4. Due to the rigid portion 23 extending into the reservoir 22, the side wall 15 of the cap portion 14 cannot be so squeezed that opposite sides will 60 meet and cut off the flow of the liquid C.

As the liquid C leaves the outlet 18, it will be guided to the bristles 22 by the projection 24 and will not drip in a direction away from the bristles.

The liquid-coated bristles may now be brushed 65 over the nails, applying the liquid C thereto and, since the flow of liquid may be readily varied, the user will quickly be able to learn how much of a pressure to apply to the cap portion 14 in order to eject sufficient liquid to apply a coating desired.

Because of the viscosity of the liquid C and its 70 rapidity in drying, the flexibility of the cap portion 14 allows the rubber thimble referred to, housing the rigid portion 23, to oscillate to some extent and agitate the liquid at the outlet end

of the applicator so that there is less tendency of the liquid there to become more viscous due to the entrance of air into the receptacle 21, replacing the volume of liquid C ejected from the applicator.

Various changes may be made to the form of invention herein shown and described, without departing from the spirit of the invention or the scope of the following claims.

What is claimed is:

1. In a reservoir-containing liquid applicator, a tubular portion of rigid material closed at one end and provided with a hollow cap portion at its other end, said cap portion being of flexible material and having a restricted outlet, said cap portion extending a substantial distance beyond said last named end of said tubular portion, applicator means carried by said cap portion closely adjacent said outlet, and extending outwardly from said cap portion, and combined drip-preventing and guide means for said liquid, including a baffle extending from the exterior surface of said cap portion adjacent said outlet, and with said outlet between said baffle and said applicator means, said baffle extending toward 25 said applicator means.

2. In a hand applicator for a viscous liquid, an elongated hollow body portion having a side wall and end walls, providing a reservoir for said liquid, and provided with a restricted outlet 30 through one of said end walls, said last named end wall and a section of said side wall adjacent said last named end wall being of flexible material, a thimble of flexible material carried by said flexible end wall, said thimble projecting into said reservoir, being spaced from the side wall of said body portion and having a mouth extending through said flexible end wall, an applicator means, including a rigid portion and a flexible portion gripped by and extending from 40 said rigid portion, said rigid portion being gripped by the wall of said thimble, and said flexible portion extending outwardly from said flexible end wall, said restricted outlet being disposed closely adjacent said mouth whereby, because 45 said thimble and said end wall are of flexible material and said thimble is spaced from said side wall, said thimble may oscillate while gripping said rigid portion.

3. In a hand applicator for a viscous liquid, 50 an elongated hollow body portion having a side wall and end walls, providing a reservoir for said liquid, and provided with a restricted outlet through one of said end walls, said last named end wall and a section of said side wall adjacent said last named end wall being of flexible material, a thimble of flexible material carried by said flexible end wall and projecting into said reservoir, being spaced from the side wall of said body portion and having an imperforate 55 inner end, said thimble having a mouth extending through said flexible end wall, and applicator means, including a portion gripped by the wall of said thimble and extending into said thimble to adjacent said closed inner end, and a portion extending outwardly from said flexible end wall, said restricted outlet being disposed closely adjacent said mouth.

4. In a reservoir-containing liquid applicator, a tubular portion of rigid material closed at one 70 end and provided with a hollow cap portion at its other end, said cap portion being of flexible material and having a restricted outlet, said cap portion extending a substantial distance beyond said last named end of said tubular portion, ap- 75

5 plicator means carried by said cap portion closely adjacent said outlet, and extending outwardly from said cap portion, and combined drip-preventing and guide means for said liquid, including a baffle extending from the exterior surface of said cap portion adjacent said outlet, and with said outlet between said baffle and said applicator means, said baffle extending toward that portion of said applicator means which projects 10 outwardly beyond said cap portion.

6. In a reservoir-containing liquid applicator, a tubular portion of rigid material closed at one end and provided with a hollow cap portion at its other end, said cap portion being of flexible material and having a restricted outlet, said cap portion extending a substantial distance beyond said last named end of said tubular portion, applicator means carried by said cap portion closely adjacent said outlet, and extending outwardly 15 from said cap portion, and combined drip-preventing and guide means for said liquid, including a baffle extending from the exterior surface of said cap portion adjacent said outlet, and with said outlet between said baffle and said applicator means, said baffle extending toward that portion of said applicator means which projects 20 outwardly beyond said cap portion, said

baffle being of less width than the greatest diameter of said cap portion.

7. In a reservoir-containing liquid applicator, a tubular portion of rigid material closed at one end and provided with a hollow cap portion at its other end, said cap portion being of flexible material and having a restricted outlet, said cap portion extending a substantial distance beyond said last named end of said tubular portion, applicator means carried by said cap portion closely 5 adjacent said outlet, and extending outwardly from said cap portion, said outlet being disposed wholly to one side of said applicator means where said applicator means emerges from said cap portion, and having a portion of the wall 10 of said cap portion between said opening and said means, the axis of said opening being in substantial parallelism with the longitudinal axis of said applicator means, and combined drip-preventing and guide means for said liquid, including 15 a baffle extending from the exterior surface of said cap portion adjacent said outlet, and with said outlet between said baffle and said applicator means, said baffle extending toward said applicator means. 20
